ELECTRICAL CONNECTION

Howard A. Sheward, Janesville, Wis.

Application January 12, 1933, Serial No. 651,319

1 Claim. (Cl. 173—324)

This invention pertains to electrical connections, and more particularly to a cord connection for all types of electrical appliances, such as sad-
5 irons, cooking appliances, electric clippers, vibrators, and the like.

The invention has primarily for its object to provide a comparatively simple, durable, and efficient electrical cord connection of either the socket or plug type, and comprising means for permitting free universal movement of the cord with constant positive electric connection in all 10 positions.

Incidental to the foregoing, a more specific object resides in the provision of an electrical connection embodying a universal joint of the ball and socket type, in connection with novel means for maintaining the electrical contact between relatively movable parts.

With the above and other objects in view, which 20 will appear as the description proceeds, the invention resides in the novel construction, combination and arrangement of parts, substantially as hereinafter described and more particularly defined by the appended claims, it being understood 25 that such changes in the precise embodiment of the herein disclosed invention may be made as come within the scope of the claims.

In the accompanying drawings is illustrated one complete example of the physical embodiment of the present invention constructed according to the best mode so far devised for the practical application of the principles thereof.

In the drawings:—

Figure 1 is a longitudinal section through a connection constructed in accordance with the present invention, the same being taken on the line 1—1 of Figures 2 and 4.

Figure 2 is a similar section taken on the line 2—2 of Figures 4 and 5.

Figure 3 is an elevation with parts broken away and in section.

Figure 4 is a transverse section taken on the line 4—4 of Figure 2, and

Figure 5 is a transverse section taken on the line 5—5 of Figure 2.

Referring now more particularly to the accompanying drawings, the numeral 1 designates a body member formed from any suitable insulating material, and preferably composition material, such as "Bakelite", which may be cast in suitable dies. The body member 1 comprises a boss 2 having formed thereon adjacent one end a semi-spherical head 3. Formed on the opposite end of the boss is one section of a split casing 4, 50 which serves to house the wiring connections for

the cord, as will be hereinafter explained. Co-operating with the casing section 4, and complementary thereto, is a cover section 5, provided with a cut-out portion 6 in its rear end, which straddles the boss 2, as best shown in Figure 1. 5

Surrounding the body member 1 is a metallic shell 7, which is split longitudinally to form upper and lower sections 8 and 9, respectively, while the upper section 8 is split transversely intermediate its ends and adjacent the cover section 5 10 of the contact housing, thus forming a removable plate 10, which renders access to the contact housing when desired. As best shown in Figure 1, the two sections 4 and 5 of the contact housing, as well as the sections 9 and 10 of the outer shell, 15 are locked together in assembled position by means of a bolt 11 having a barrel nut 12 threaded on its lower end. The forward end of the outer shell is cut out for reception of a cushioning ferrule 13, through which the cord passes, as indicated in dotted lines in Figure 1. Obviously, the ferrule prevents contact between the cord and outer shell, and being preferably formed from resilient material, such as rubber, prevents wear 20 and mutilation of the cord. 25

The rear ends of the outer shell sections terminate in semi-spherical portions 14, which are shaped to the semi-spherical head 3, and project beyond the same to form a complete closure for the universal connection, regardless of the relative position of the parts, as will be hereinafter explained more in detail. 30

Projecting longitudinally through the boss 2 of the body member is a stud 15, having a ball 16 threaded on one end concentrically with the spherical head 3, while the opposite end has secured thereon a contact strip 17, preferably cast into the boss 2, and secured to the end of the rod 15 by a nut 17', which is subsequently covered with suitable insulating material 18, as best 40 shown in Figure 2. The exposed portion of the contact member 17 is provided with a threaded recess for reception of a screw 19 for attachment of the wire. In addition to the contact 17 a second contact strip 20 is provided, which is preferably cast into the boss 2 and embedded in the inner face of the spherical head 3. The boss 2 is provided with a cut-out recess 21 adjacent its outer end, which exposes the end of the contact strip 20 for attachment of one of the wires of 50 the electric cord by means of the screw 22.

Here it will be noted that the opposite sides of the lower casing section 4 are provided with angular notches 23 alined with the contact screws 19 and 22, in order to permit the use of 55

a screw driver, or other tool, in attaching the wires of the cord to the contacts. The upper casting section 5 is provided on its edges with nibs 23, corresponding to the notches 23 and forming 5 a closure therefor when the casing is assembled. Also, in order to relieve strain upon the wiring connections, the boss 2 has formed thereon the lateral projections 24, around which the cords are turned prior to attaching the wires to the contacts, as best illustrated in Figure 1.

10 While the present invention may be embodied in connections of various types, the present form illustrated comprises a wall plug including a head 25, which carries the usual prongs 26 and 27, 15 preferably cast into the head, as shown in Figure 2, wherein it will be seen that the prong 26 projects through the head and is embedded in the boss 28, which is provided with a shoulder 29 adjacent its inner end, for reception of a semi-spherical contact shell 30, secured on the boss by upsetting the end of the prong 26. Also, in order 20 to provide secure, rigid connection between the contact shell 30 and the boss 28, an anchor strip 31 may be cast into the boss, as shown in Figure 25 3, its outer end being upset over the shell 30.

As best shown in Figure 2, the prong 27, which is embedded in the head 25, is secured on the stud 32 by means of a nut 33, the same being 30 subsequently covered by suitable plastic insulating material 34. Threaded on the opposite end of the stud 32 and abutting the end of the boss 28, is a ferrule 35, which is exteriorly threaded for reception of the retaining nut 36, that engages the ball 16 to provide a universal connection between the body member 1 and the stationary plug section, which carries the prongs 26 and 27. To 35 frictionally hold the relatively movable sections in adjusted position, and at the same time compensate for any wear that may occur in the ball and socket connection, a washer 37 is positioned within the ferrule 35 and is provided with a spherical seat for reception of the ball 16. A spring 38, disposed between the ferrule and washer 37, serves to frictionally hold the washer 37 into engagement with the ball 16.

40 In order to provide constant electrical contact between the relatively movable parts, a sector 39 is secured to the inner face of the semi-spherical head 3 and is connected to the contact strip 20 by a rivet 40, or any other suitable form of connection. Projecting from the sector 39 at suitably spaced intervals are the resilient contact fingers 41, which engage the spherical contact shell 30, thus forming an electrical connection be-

5 tween the prong 26 and the contact strip 20. The electrical connection for the contact 17 is obtained through the rod 15, the ball and socket connection and the stud 32. Thus it will be seen that regardless of the relative position of the movable parts, contact is maintained at all times, and inasmuch as a plurality of contact fingers are provided, which resiliently engage the contact shell 30 at spaced intervals, possibility of arcing, with 10 consequent deterioration of the contact fingers, is reduced to a minimum.

15 In order to provide a complete closure for the universal connection, and prevent exposure of the contacts, a transversely split shell 42 is mounted on the head 25, it being noted that a slight clearance is provided between the section 43 and the spherical end of the shell 7, which permits the spring 38 to take up any wear that might occur in the ball and socket connection. The outer section 44 snugly engages the shell 7, and 20 is provided with spaced radial ears 45 secured to the finger projections 46, formed on section 43, by means of bolts 47.

25 From the foregoing explanation, taken in connection with the accompanying drawings, it will be readily seen that a comparatively simple and durable universal connection has been provided for electrical cords utilized upon various types of appliances, which permits free universal movement of the cord and eliminates frequent breakage often accompanied by serious damage through arcing, as well as injury to the user. It will also be seen that the connection is exceedingly neat and attractive in appearance, and, because of its compactness, the same can be readily employed 30 wherever plug connections are used.

35 I claim:

An electrical connection comprising an insulated body member embodying a boss and a semi-spherical head carried thereby, a split casting surrounding said boss and head, electric terminals carried by said boss, a movable plug provided with electrical contacts, a semi-spherical contact shell carried by said plug, resilient fingers engaging said shell and connected with one 40 of the terminals carried by said boss, a ball and socket coupling between said body member and plug, said coupling having electrical contact with the other of said terminals carried by the boss, and a split spherical shell carried by said plug 45 and body member to form a complete housing therefor, the sections of said shell having relative universal movement.

HOWARD A. SHEWARD.
